UNITED STATES PATENT OFFICE.

LEWIS A. DARE, OF SEATTLE, WASHINGTON.

DESIGN FOR A HOSPITAL INDICATING CASING.

Application filed November 18, 1926. Serial No. 19,766. Term of patent 3½ years.

To all whom it may concern:

Be it known that I, LEWIS A. DARE, a citizen of the United States, residing at Seattle, in the county of Kings and State of Washington, have invented a new, original, and ornamental Design for a Hospital Indicating Casing, of which the following is a specification, reference being had to the ac-

companying drawing, forming part thereof.

Figure 1 is a front elevation, and Fig. 2 is a side elevation of a hospital-indicating casing, showing my new design.

I claim:

The ornamental design for a hospital indicating casing, as shown.

LEWIS A. DARE.
